(54) **SLITTING, TIMBER**

(76) Inventor: **William Barker**

William Parker. Letter Patent Date 25th March 1826.

The schedule referred to in these Letters Patent and making part of the same, containing a description in the words of the said William Parker himself of his improvement being a machine for dividing or slitting lumber, boards &c.

My invention consists in forming a frame box or plane of one, two or more pieces of wood or metal of a box suitable for the work to be performed; what I shall now describe is one for common three quarter stuff.

Take a piece of seasoned wood of about 15 inches long and 3 1/2 inches square: Similar to a common plane in shape with a handle on the upper side. Out of the centre of this plane is cut an opening an inch and a half deep and three quarters of an inch wide, running through from end to end. Through the sides of this box plane or plane due cut three or more oblong mortices facing each other. These mortices are filled by wedges or blocks under which are put knives angled towards the stuff to be cut. The first two knives or cutters do not cut on the stuff more than one eighth of an inch, the second about a quarter of an inch or so as to cut the board about half through; and the third knife or blade or cutter just to divide it entirely. These knives are placed about half an inch from the bottom of the plane. The first and third ones within, an inch and a half of each other and the second one between them.

Instead of the knife or cutter described rollers made half an inch wide the size may be used as circumstances may require and the depth of them may be regulated by the opening above the cutter.

If it be necessary several rows of knives, rollers or rollers may be made use of to cut a board in very small strips. Three knives in a row I think best.

When thick stuff is to be slit, it will be necessary to use a strong windlass and strap by horse or manual labour to pull the slitting machine through the stuff.

The operation. The stuff if it be of an ordinary kind is put on an edge in the tool reversed as may be thought proper. If the stuff be on an edge, the plane is presented to its front end and a small incision takes place; it is moved on a short distance and is half cut through; and by the time it goes the length of the plane, it is entirely cut through.

What I claim, as my invention, is, a frame box or plane, with one, two, three or more knives or cutters, directly opposite each other, three on each side, to be regulated by wedges, or screws, for the cutting of timber, boards, or any thing, else to which it may be applied.

Witnessed,

Robert Sittle
John P. Elliot.

William Barker.
